DOOR OPEN SIGNAL SYSTEM

Karol Zajc, New York, N. Y.

Application March 20, 1945, Serial No. 583,764

4 Claims. (Cl. 177—311)

1

This invention relates to new and useful improvements in safety contact double door opener switch.

It is customary to mount an electric lock upon the jamb of a door and to mount the keeper on the door. With this arrangement when the push button is depressed it operates the electric lock which keeps on operating and making a noise as long as the push button switch is held down. This invention proposes to mount the electric lock upon the door and to mount the keeper upon the door frame or jamb. It is proposed to provide certain cooperative contacts mounted on insulation members on the door, and door jamb which engage each other only when the door is closed. These contacts are connected up in an electric circuit for controlling the electric lock. Now when the push button switch is closed for opening the lock, the current to the electric lock will be instantly cut when the door is opened. This stops the operation of the electric lock and the noise even though the push button is held down.

The invention also proposes to associate a bell or signal with the door which will operate when the door is opened. It is proposed to mount a certain control switch for the bell on the door jamb so that when the door is closed the push button of the switch is depressed. It is proposed to associate certain mechanisms with the push button switch so as to control operation of the bell or signal in desired way.

Still further the invention proposes the construction of a hinged door and associated mechanism as briefly explained, which is very desirable, simple in construction and which may be manufactured and sold at a low cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary elevational view of a closed door provided with mechanism construction in accordance with this invention.

Fig. 2 is a fragmentary perspective view of a portion of the door frame and the door illustrating some of the mechanism, in detail.

Fig. 3 is a fragmentary enlarged vertical sectional view taken on the line 3—3 of Fig. 2.

Fig. 4 is a fragmentary transverse vertical sectional view taken on the line 4—4 of Fig. 3.

2

Fig. 5 is a fragmentary sectional view taken on the line 5—5 of Fig. 2.

Fig. 6 is a perspective view of another portion of the door and door frame disclosing another part of the improved mechanism.

Fig. 7 is a fragmentary enlarged vertical sectional view taken on the line 7—7 of Fig. 6.

Fig. 8 is an enlarged detailed view similar to Fig. 7 disclosing a modified form of the invention.

Fig. 9 is a schematic wiring diagram of the device shown in Fig. 8.

The new and improved safety contact double door opener switch, in accordance with this invention is shown used in combination with a hinged door 10. This hinged door 10 is mounted in a usual door frame, or door jamb 11, with the usual hinge 12. An electrically operated lock 14 is mounted upon said door 10 and is cooperative with a keeper 15 mounted in the door jamb.

Insulation members 16 and 17 are mounted upon said door jamb, or frame 11, and on said door 10 in a position to be adjacent each other when the door is closed. A pair of contacts 18 are mounted upon the insulation member 16 and are cooperative with a pair of contacts 19 mounted upon the insulation member 17.

The insulation members 16 and 17 are in the nature of boxes constructed of insulation material. These boxes are mounted in recessed portions formed in the door jamb, and in the door, and held in position with fastening elements, or screws 20. Each of the insulation boxes 16 and 17, has an opening through which electric cables such as cables 22 and 23 may enter. The contacts 18 are fixedly mounted. Leads from the cable 22 connect with the inner ends of the contacts 18. The contacts 19 are in the nature of push buttons. Each of these contacts are slidably mounted in a socket 24. Each of the contacts 19 has an interior stem 25. Expansion springs 26 are mounted upon the stems 25 and act between stationary insulation member 27 and the contacts 19 for normally urging the contacts 19 into slightly projected positions.

Insulation members 27 are stationarily mounted within the box-like insulation member 17. The leads from the cable 23 are connected with the inner ends of the stems 25 so as to indirectly connect with the contacts 19. The cable 23 electrically connects with the electric lock 14, see Fig. 1, by which the necessary current may be supplied to the lock. The cable 22 connects with the usual push button control switch, not shown, and electric current supply for the operation of the electric lock. For example, in homes, the outer doors

are usually closed with electric locks so that tenants on upper floors may open the door downstairs by pressing push buttons.

An important feature of the new construction hereabove disclosed, resides in the fact that when the door 10 is closed it is possible to operate the electric lock 14 by sending an electric current through the cable 22. The current from the cable 22 will reach the leads of the cable, which are connected with the contacts 18. When the door is in its closed position, the contacts 18 engage said contacts 19 so that the electric current passes through the cable 23 to the electric lock 14. As soon as the door is opened, the electric current will be broken, because the contacts 18 and 19 will be separated. Now the electric lock 14 stops operating, and stops making noise, even though the push button switch, not shown, controlling the cable 22 is held closed.

In Figs. 6 and 7 a further embodiment of the invention has been disclosed in which the door frame 11, or jamb is provided with a push button switch 30 for controlling an electric bell, not shown on the drawing. The push button switch 30 includes a box-like insulation member 31 which is mounted on the door jamb, or frame 11 with fastening elements 32. A push button 33 of insulation material, normally projects from the insulation member 31. This push button 33 is provided with an interior stem 34 connected with one of the leads of a cable 35. A spring 36 is coaxially mounted on the stem 34 and acts against a stationary member 37 mounted upon the insulation member 31. The spring 36 acts against the button 33 to urge it into an extended position.

The button 33 carries a contact 38 which engages a contact 39, when the push button 33 is in its extended position. The contact 39 is connected with the other lead of the cable 35. When the door 10 is opened, the push button 33 will be extended by the spring 36, and the contacts 38 and 39 will engage each other closing the switch and operating an electric bell, not shown. The signal thus given will indicate that the door is still open. As soon as the door is closed, the button 33 will be depressed opening the switch 30. The bell then stops ringing.

In Figs. 8 and 9 still another form of the invention has been disclosed which is very similar to the form shown in Figs. 6 and 7 but distinguishing in the fact that a new and improved control for the ringing of the bell, has been provided. This control will operate the bell in a certain way. More specifically, the bell 40 is connected in an electric circuit 41 which includes in series said bell 40, a circuit interrupter 42, a high resistance 43 and the contacts 38 and 39. The circuit interrupter 42 may be in the nature of a bi-metal thermostat which bends away from a stationary contact 44 when it becomes heated and bends towards and engages the stationary contact 44 when cool. A shunt circuit 46 bi-passes the high resistance 43 and said circuit 42, and includes in series a contact arm 47 and a bi-metal thermostat 48 controlling the shunt circuit 46.

The contact arm 47 is resiliently urged against the end of the bi-metal thermostat 48 by a spring 50. The contact arm 47 is pivotally mounted on a stationary bracket 51. A control rod 52 is slidably mounted in stationary brackets 53 and connects with the contact arm 47 for moving the contact arm into a "loaded" position, as will become clear as this specification proceeds. The stem 34 is provided with an arm 55 made of

insulation material for moving the rod 52, and so indirectly moving the contact arm 47 into its "loaded" position.

In other respects this form of the invention is identical to the prior form and like parts may be recognized by like reference numerals.

The operation of this form of the invention is as follows:

When the door 10 is closed the push button 33 is in this depressed position and the contacts 38 and 39 are out of contact with each other. Therefore the bell circuit 41 is open. When the door 10 is open the push button 33 will be moved outwards by the spring 36. This indirectly causes the contact 38 to engage the contact 39. The bell circuit 41 is now closed. An electric current will flow through the low resistant contact arm 47, the low resistant bi-metal thermostat 48 and the shunt circuit 46. This causes the bell 40 to ring loudly because it is receiving full current.

An instant later, the bi-metal thermostat 48 will flex downwards, as indicated by the dot and dash lines 48' in Fig. 8. This causes the contact arm 47 to move upwards to the dot and dash line position 47'. The circuit is now open through the shunt 46. The current will therefore flow through the high resistance 43 and through the bi-metal thermostat 42. The bell will now ring weakly. An instant later the thermostat 42 will open and the bell will stop ringing. The next instant the thermostat 42 will close and the bell will ring again. This weakly intermittent ringing of the bell will continue until the door is closed. Then the contact 38 is moved away from the contact 39 and the alarm circuit 41 is open.

When the push button 33 was moved inwards by the closing of the door, the arm 55 will engage against the rod 52, moving the rod 52 and indirectly moving the contact arm 47 back to its "loaded" position against the edge of the thermostat 48. The parts are now in their original positions.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with a hinged door, an insulation housing having mounted on the jamb of said door, a push button projecting from said housing to be pressed inwards when said door is closed, resilient means urging said push button outwards, a stationary contact within said housing and a contact carried by said push button to engage said stationary contact when said push button is extended, a bell circuit including in series said contacts and a high resistance circuit interruptor, a shunt circuit by-passing said high resistance and circuit interruptor and including in series a contact arm and a bi-metal thermostat, means for pivotally supporting said contact arm, means for resiliently urging said contact arm against said bi-metal thermostat when the latter is cool and past the thermostat when the latter is warm, and means operated by said push button for resetting said contact arm against said thermostat when said push button is depressed.

2. In combination with a hinged door, an insu-

lation housing having mounted on the jamb of said door, a push button projecting from said housing to be pressed inwards when said door is closed, resilient means urging said push button outwards, a stationary contact within said housing and a contact carried by said push button to engage said stationary contact when said push button is extended, a bell circuit including in series said contacts and a high resistance circuit interruptor, a shunt circuit by-passing said high-resistance and circuit interruptor and including in series a contact arm and a low resistance bimetal thermostat, means for pivotally supporting said contact arm, means for resiliently urging said contact arm against said bimetal thermostat when the latter is cool and past the thermostat when the latter is warm and means operated by said push button for resetting said contact arm against said thermostat when said push button is depressed, said means for pivotally supporting said contact arm including a support bracket.

3. In combination with a hinged door, an insulation housing having mounted on the jamb of said door, a push button projecting from said housing to be pressed inwards when said door is closed, resilient means urging said push button outwards, a stationary contact within said housing and a contact carried by said push button to engage said stationary contact when said push button is extended, a bell circuit including in series said contacts and a high resistance circuit interruptor, a shunt circuit by-passing said high resistance and circuit interruptor and including in series a contact arm and a low resistance bimetal thermostat, means for pivotally supporting said contact arm, means for resiliently urging said contact arm against said bimetal thermostat when the latter is cool and past the thermostat when the latter is warm and means operated by said push button for resetting said contact arm against said thermostat when said push but-

ton is depressed, said means for pivotally supporting said contact arm including a support bracket, and said resilient means comprising a spring acting between said bracket and said arm.

- 5 4. In combination with a hinged door, an insulation housing having mounted on the jamb of said door, a push button projecting from said housing to be pressed inwards when said door is closed, resilient means urging said push button outwards, a stationary contact within said housing and a contact carried by said push button to engage said stationary contact when said push button is extended, a bell circuit including in series said contacts and a high resistance circuit interruptor, a shunt circuit by-passing said high resistance and circuit interruptor and including in series a contact arm and a low resistance bimetal thermostat, means for pivotally supporting said contact arm, means for resiliently urging said contact arm against said bimetal thermostat when the latter is cool and past the thermostat when the latter is warm, and means operated by said push button for resetting said contact arm against said thermostat when said push button is depressed, including an arm connected with said push button, a rod to be moved by said button and connected with said contact arm.
